UNITED STATES PATENT OFFICE.

LEWIS M. HAUPT, OF CYNWYD, PENNSYLVANIA.

BEACH-RECLAMATION SYSTEM.

Application filed February 4, 1924. Serial No. 690,377.

To all whom it may concern:

Be it known that I, LEWIS M. HAUPT, a citizen of the United States, residing in Cynwyd, county of Montgomery, State of Pennsylvania, have invented a new and useful Beach-Reclamation System, of which the following is a specification.

My invention relates to a beach reclamation and protection system or work, and has relation to the system described in my Letters-Patent No. 1,010,139, dated November 28, 1911. As in the case of that invention, the general purpose of the present invention is to control and direct the natural forces of wind, wave, current and tide in such manner that they will accomplish the useful ends of protection and reclamation, instead of destruction.

Specifically, the objects of the present invention are to increase greatly the efficiency of the work referred to, especially for the recovery and restoration of beaches which have been carried away, whether by gradual and continuous tidal and wave action, or suddenly, by violent storms; and to accomplish this result at a cost materially less, both for construction and maintenance, than is obtained by the usual bulkheads supplemented by spur-jetties or "groins."

The principal features of the present invention are the combination with the wave decomposing jetties (such as are described in my former patent) of an impounding basin or basins, adjacent to the shore-end thereof which serve to decompose the attacking maritime forces, and render them inert from harm and to form impounding sandy barriers or reservoirs at their bases, especially where abutments are necessary to avoid a flanking movement, and to protect the reentrant angle caused by bulk-heads and the normal spur jetties, thus affording protection to life and property and increasing the durability of the structures. By the means indicated, and herein described, later, in detail, the winds are caused to cooperate with the waves, in reinforcing the strand and reclaiming a more permanent beach, automatically.

The invention consists of the novel con-

struction hereinafter described and finally claimed.

The nature, characteristic features and scope of the invention will be more fully understood from the following description taken in connection with the accompanying drawings forming part hereof, and in which:

Fig. 1, is a view of a reclamation jetty with its supplementary devices for the decomposition of the erosive forces and their conversion into constructive elements, by precipitating the sand or shingle within the retaining enclosures, thus building dunes.

Fig. 2, is a detailed view indicating the character of the structure and the means employed to render it relatively permanent by connecting it with the strand to be protected, instead of laying it on the surface of the ground, to be swept off by storms.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described, but can be adapted to local physical conditions.

The function of the reclamation jetty portion is to retard and decompose the offshore forces and to direct them obliquely up the beach without at the same time arresting the drift entirely on the windward side, and robbing the leeward sector; while the purpose of the impounding reservoirs in the groins, is to create, in combination with the reclamation jetty, as a feeder, a trap to receive and store the drift thus driven up by the sea, and to protect the hinterland from overflow by storm tides, which destroy or impair the use of highways, roads, or dwellings.

Referring to the drawings specifically, there is shown in Fig. 1, a typical reaction jetty in combination with the buffers 1, com-

posing the basins 2, for the protection of the groins 3, which are not provided in my former patent, where the normal bulkhead or bank constituted the barrier, causing reaction, undermining and great injury to the walls or other barriers which are overtopped and ruptured.

In the present invention, the buffers 1 are made concave to advancing seas and have entrances 4 at both ends which are contracted so that the waves are broken and the segments entering the curved flanks made to meet inside in the broader sections and by opposition check the advance and precipitate their sediment, thus constituting a settling basin 2 and wave breaker at small cost, and rapidly protecting the jetty and the adjacent property from loss. The buffers 1 are braced by strips of timber 6.

In Fig. 2, there is shown the character of the construction and the general method of bracing consisting of piles 5, having the proper penetration thus anchoring them to the subsoil and bracing them, as at 6', so rigidly as to prevent vibration from the most violent storms, and causing the structure to deposit and hold the drift so that in many cases it becomes buried under the deposits which it creates and thus becomes permanent. The bracing 6' consists of criss-cross struts arranged between adjacent lines of piles 5.

No claim is made however for connecting the structure with the foundation, which is the usual method, but merely the adjustment of the cooperative devices for the retention and rapid upbuilding of these additional factors to increase efficiency and permanency while reducing cost by the omission of rock and brush filling, so generally required in this class of structures.

In carrying out my invention, I dispense, therefore, with all dikes, sea-walls, spurs, groins and similar structures of earth, stone, wood, or other materials singly or in combination. The only material required is wood in the form of piles 5 and bracing 6, (not as in that of cribs or caissons,) with the necessary bolts, spikes, stringers and batter-piles and other attaching devices to maintain the rigidity of the structure, which is not designed to be water-tight, but on the contrary to be sufficiently permeable and non-resistant so as to permit said to pass freely through, while high enough to check the waves of ordinary storm-tides.

Thus economy in first cost as well as economy in maintenance is effected; the efficiency of the system is readily increased by the more rapid accumulation of sand impounded in situ; and eventually is reduced to little or nothing for maintenance, when the structure is buried under the sand which it has impounded on both flanks and beyond its extremity.

The lengths, grades, radii, and location as well as the degrees of curvatures of its several elements may vary within wide limits, depending upon the local physical conditions and the exposures to the attacking forces of the seas.

An additional factor in the protection and reclamation of alluvial beaches is that of permeability, for in practice it is customary to build them tight, whether of stone or wood, to prevent the waves from passing through and to arrest the sediment they may carry and retain it in the windward groin, thus robbing the lee, and converting the jetty into a "hurdle," causing the surge to roll over and denude the opposite flank, with injury to abutting properties.

This may readily be prevented by dispensing with the rock and brush filling; or the use of tight sheathing piles, and by placing only the barrier piles, whether in one or two rows, as may be required, in juxtaposition as shown in Fig. 2, so that the surcharged waves may be checked, in part, yet pass through and deposit their sediment equally in both flanks or groins, and thus not destroy the continuity of the surface of the beach, while at the same time, the cost is reduced and the efficiency nearly doubled, as the number of such jetties will be reduced some fifty per cent or more, in addition to the saving in the cost of construction.

It will now be apparent that I have devised a novel and useful combination which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. In a beach-reclamation system, the combination of a jetty extending out from the shore, and curtains on the flanks thereof and separated therefrom forming therewith impounding basins for the automatic accumulation and retention of drift material, said curtains being formed upon arcs of circles.

2. A beach-reclamation-work comprising in combination, a wave-decomposing jetty and an auxiliary curtain separated therefrom and constituting therewith an impounding basin, said curtains being concavely arranged with respect to advancing seas.

3. A beach-reclamation-work comprising the combination of a jetty so placed as to de-

compose the marine forces and create a lee, said jetty having its flanks spread at the shore end to cooperate with an auxiliary curtain, and a separate curved flank curtain

5 forming with said jetty an impounding reservoir, said flank curtain being concave to advancing seas.

4. A permeable, reclamation jetty, having

on its flanks impounding reservoirs formed by flank members, said members being concave to advancing seas and separated from said jetty. ¹⁰

In witness whereof, I have hereunto signed my name.

LEWIS M. HAUPT

Certificate of Correction.

It is hereby certified that in Letters Patent No. 1,575,362, granted March 2, 1926, upon the application of Lewis M. Haupt, of Cynwyd, Pennsylvania, for an improvement in "Beach-Reclamation Systems," errors appear requiring correction as follows: In the drawing, for the numeral "6" in the center of Figure 2 read 6'; page 2 of the specification, line 54, for the word "said" read *sand*; and that the said Letters Patent should be read with these corrections therein that the same may conform to the record of the case in the Patent Office.

Signed and sealed this 27th day of April, A. D. 1926.
